UNITED STATES PATENT OFFICE.

THEODORE PRATT, OF GLEN COVE, NEW YORK.

INTERNAL-COMBUSTION ENGINE.

Application filed January 6, 1921. Serial No. 435,451.

To all whom it may concern:

Be it known that J. THEODORE PRATT, a citizen of the United States, and a resident of the town of Glen Cove, county of Nassau, 5 and State of New York, have invented certain new and useful Improvements in Internal-Combustion Engines, of which the following is a specification, reference being had to the accompanying drawings.

- 10 It is the purpose of this invention to construct the piston and co-acting parts of the cylinder of an internal-combustion engine in such manner that the engine shall be absolutely valveless and the piston positively 15 driven at the end of each stroke. To that end the cylinder is provided with extension chambers at its opposite ends and the piston is provided with corresponding extensions, which, during its reciprocations, move plunger-like through the extensions of the cylinder. The piston is so constructed that certain gas passages are provided arranged in such manner that at each reciprocation of the piston, the fuel is compressed and transmitted from the fuel intake to the explosion chambers in which the fuel is alternately compressed and fired, so that at each reciprocation of the piston, a propelling impulse is applied upon its opposite sides alternately, 25 thus in a speedy, economical and desirable manner effecting the generation of power, which, through the usual instrumentalities, is conveyed to the crank shaft of the machine. The exhaust port is located at or 30 near the longitudinal center of the cylinder and the intake ports from the piston open into the explosion chambers of the cylinder at or near their ends, so that at each reciprocation of the piston, the exhaust occurs at 35 points as far as possible from the respective intakes, and since the incoming charges are under pressure, the exhaust is made positive and the scavenging of the spent products assured.
- 40 Referring to the drawings, Fig. 1 is a longitudinal sectional view; Fig. 2 is a cross sectional view of the central part of the piston taken on the line 2—2 of Fig. 1; Fig. 3 is a cross sectional view of the central 45 part of the piston taken on the line 3—3 of Fig. 1; Fig. 4 is a sectional view taken on the line 4—4 of Fig. 1; Fig. 5 is a longitudinal sectional view of a modified construction of the piston removed from the 50 cylinder.

In the drawings 1 represents the cylinder, 2 the water jacket, 3 the crank shaft, 4 the crank, 5 the crank shaft casing, 6 the piston rod, 7 the connecting rod, 8 the stuffing box, 9 the intake for the fuel, 10 the exhaust, 11 60 the water intake, 12 the water outlet, 13, 13' the spark plugs. These parts may be of any preferred and suitable construction.

Referring now to the parts more immediately involved in this invention. 14 is the 65 central part of the piston which may be a forging or casting, as preferred, and which has suitably connected to its opposite sides extensions 15 and 16 respectively, and internal tubular structures 17 and 18, which 70 respectively are located within the extensions 15 and 16 and connected to them in any preferred manner, as by welding, brazing or threading, with suitable packing where desired. The central member 14, see 75 best Figs. 2 and 3, has through its central part in the instance illustrated openings 19, 19, and 20, 20 arranged in two pairs, and two collar-like parts 21 and 22 projecting respectively from its opposite sides, as 80 seen best in Fig. 1. These collar like devices guide and control the passage of the fuel from one side of the piston through it to the other side as hereinafter explained. These collar-like parts are so formed as to 85 flare outwardly at opposite parts of the circumference, thus producing oppositely located recesses, and in the bottom of each recess the passageways or openings 19 and 20 are located which extend through the 90 casting 14, so that during the appropriate reciprocation of the piston the fuel will be made to pass alternately from one side to the other of the piston through the openings 19 and 20. The extension 15 of the 95 piston has three sets of packing 23, which may be of any preferred form. Two of them are located by the sides of the gas intake ports 24, 24, and one of them, as shown, in an extension or skirt 25 from the extension, and on the opposite side of the piston there are two sets of packing 26. These packings may be of any preferred construction.

27 is a chamber in the cylinder below the 105 piston (see Fig. 1), enlarged when the piston is elevated, and 28 is a similar chamber in the cylinder at the opposite end from the chamber 27. The chamber 28 is shown practically closed because of the position 110

2
of the piston. 29 is an explosion chamber at one side of the piston and 30 is a similar explosion chamber at the opposite side of the piston. The exhaust 10 is located 5 between them. 31, 31 are ports in the cylinder with which the ports 24, 24, in the piston register during the movements of the piston as hereinafter described. 32, 32 are 10 ports in the piston similar to the ports 24, and 33 are ports in the cylinder similar to the ports 31.

The operation is as follows:

On the assumption that the parts are in the position shown in Fig. 1, the fuel enters 15 at the intake 9 and passes through the intake port 24 into the annular chamber between the interior wall of the extension 15 and the exterior wall of the tubular member 17 and thence through the openings 20 into the interior 20 of the tubular member 18 and thence into the open chamber 27 below the piston. It will be noted that as the parts are illustrated in Fig. 1, the charge in the explosion chamber 29 is under compression. The spark 25 plug 13 being now energized, the charge in chamber 29 will be exploded, and the piston driven downwardly to the end of its stroke, at which time the exhaust ports 10 will have been uncovered, so that the exhaust of the 30 charge just exploded will take place. The downward movement of the piston has compressed the fuel in the chamber 27 and caused it to rise, and being guided and confined by the collar like parts 22 it will pass 35 again through the openings 20 into the chamber above described between the interior wall of the extension 15 and the exterior wall of the tubular member 17, so that when the piston is in its lowest position, the port 24 40 being then in registration with the port 31 in the wall of the cylinder, a fresh charge will enter the explosion chamber 29, being under some pressure, and will thus act to 45 scavenge the previous charge from the explosion chamber 29.

When the piston is in its lowermost position a fresh charge enters through the intake 9 into the enlarged space 28, which has been formed above the upper end of the 50 piston skirt 25 by the downward movement of the piston. From the space 28 the fuel will pass downwardly through the interior of the tubular member 17 and being guided and confined by the collar like parts 21 will 55 pass through the openings 19 into the annular space between the interior of the extension 16 and the exterior of the tubular member 18, so that upon the return or upward movement of the piston this new 60 charge will be compressed in the upper part of the cylinder, and when the piston has attained its uppermost position will pass through port 32 in the piston and 33 in the cylinder into the explosion chamber 30, so 65 that upon the next or downward movement

of the piston, the charge thus injected into the explosion chamber 30 will be additionally compressed, and when the piston has arrived at approximately its lowermost position the spark plug 13' being energized, this 70 charge will in turn be fired, exhausted and scavenged, with of course the appropriate action upon the piston. In this way the continued operation of the engine is secured.

In Fig. 5 I illustrate a construction which, 75 under certain circumstances, is desirable in that the entire piston structure can be readily taken apart for repair in the event of any member developing defects. In this figure the parts are numbered as follows:

34 and 35 are the extension members which are threaded as at 36 and 37 to the central casting 38, instead of being welded or brazed thereto as illustrated in Fig. 1, and the tubular members 39 and 40 respectively 80 engage with the collar-like parts 41 and 42 by simply setting their upper and lower edges into suitable annular grooves, preferably provided with lead or other suitable packing, so that when desired, the entire 85 structure may be taken apart.

Among the advantages secured by this construction of piston as compared with that of any other known to me are the following:

Lightness and minimum weight in construction because the extensions and the tubular members can be made from drawn tubing of light weight, and if desired, may be made of aluminum or other similar metal.

If one part is spoiled in the making or 100 develops defects, it can be disassembled and replaced with a perfect part, thus saving all the other suitable parts.

The construction tends to keep the fresh 105 fuel, which is cool, equally along the sides of the extensions which warms the gas and reduces the excess temperature of the extensions.

It will be obvious to those who are familiar with such matters that various modifications may be made in the details of construction of the parts above described and illustrated and yet the essentials of the invention be retained. For example, the terminal parts of the extensions 34 and 35 may 110 be threaded to the body parts thereof, instead of welding, and in such case the central casting 38 may be cast integral with the extensions 34 and 35 and the tubular members 39 and 40 may be clamped in place by the 115 threading of the terminal parts. I therefore do not limit myself to such details.

I claim:

1. In an internal combustion engine a cylinder having an extension chamber at 120 each end, a piston having an extension at each side adapted to reciprocate through the cylinder extensions, a tubular member within each piston extension, a chamber between each piston extension and each tu- 125 130

bular member entirely surrounding the latter, alternately operating fuel passages through the center of the piston whereby the fuel may pass alternately from one side 5 to the other of the piston, a fuel intake, fuel passages through the walls of the piston extensions adapted to engage respectively with the explosion chambers, and with the fuel intake port, means to fire the 10 charges and means to exhaust the products of combustion.

2. In an internal combustion engine a cylinder having an extension chamber at each end, a piston having an extension at 15 each side adapted to reciprocate through the cylinder extensions, each piston extension having a tubular member attached at one end to the central member of the piston and at the other end to the interior wall 20 of the piston extension, a chamber between the wall of each piston extension and the adjacent tubular member which entirely surrounds the latter, passageways through the central member of the piston whereby 25 fuel may pass alternately from the said chamber on one side of the piston to that on the other, an explosion chamber at each side of the piston, ports through the wall of each piston extension adapted to connect 30 respectively with the explosion chambers and with the fuel intake, means to fire the charges in both explosion chambers and means to exhaust the products of combustion therefrom.

3. An internal combustion engine comprising a cylinder having an extension chamber at each end of less diameter than the cylinder proper, a piston having a central member or piston proper, an extension 40 projecting from each side of the central member of less diameter than it, a tubular member in each piston extension, a chamber between the wall of each piston extension and each tubular member which entirely surrounds the latter, fuel passages through the central member of the piston, whereby the fuel may alternately pass from one side of it to the other, and ports through the wall of each piston extension adapted to engage 45 with the explosion chambers of the engine and with the fuel intake, means to fire the charges in each explosion chamber

and means to exhaust the product of combustion.

4. An internal combustion engine comprising a cylinder having an extension chamber at each end of less diameter than the cylinder proper, a piston having a central part, extensions projecting from opposite sides of the central part of smaller diameter than it, a tubular member in each extension connecting it with the central member at their inner ends and with the extension members at their outer ends, a fuel chamber between the walls of each extension member and the 55 tubular member within it and which entirely surrounds the latter, passageways through the central member whereby fuel may pass alternately from one of said chambers into the other and vice versa, ports 60 through the wall of each piston extension adapted to engage with the explosion chambers of the cylinder, means whereby fuel may be supplied to one of said chambers, means to fire the charges in each explosion 65 chamber and an exhaust port between the 70 explosion chambers.

5. An internal combustion engine comprising a cylinder having an extension chamber at each end of less diameter than the cylinder proper, a piston having a central part, extensions projecting from opposite sides of the central part of smaller diameter than it and detachably attached to it, a tubular member in each extension 80 detachably connected with the central member at one end and with the piston extensions at the opposite end, a fuel chamber between the walls of each extension member and the tubular member within it, passageways 85 through the central member whereby fuel may pass alternately from one of said chambers into the other and vice versa, ports through the wall of each piston extension adapted to engage with the explosion chambers of the cylinder, means whereby fuel 90 may be supplied to one of said chambers, means to fire the charge in each explosion chamber and an exhaust port between the 95 explosion chambers.

In testimony whereof I have signed my name to this specification.

THEODORE PRATT.
